UNITED STATES PATENT OFFICE.

CHARLES H. HADLEY, OF NOANK, CONNECTICUT.

IMPROVEMENT IN MECHANISMS FOR OPERATING HORSE-CAR BRAKES.

Specification forming part of Letters Patent No. 148,210, dated March 3, 1874; application filed December 11, 1873.

To all whom it may concern:

Be it known that I, CHARLES H. HADLEY, of Noank, in the county of New London and State of Connecticut, have invented certain new and useful Improvements in Brakes for Horse-Cars; and I do hereby declare the following to be a full, clear, and exact description of the invention, such as will enable others skilled in the art to which it pertains to make and use it, reference being had to the accompanying drawings, which form part of this specification, in which—

Figure 1 is an end view of a street-car with my improvement applied. Fig. 2 is a plan view of said improvement. Fig. 3 is a side view of the same.

This invention has relation to the means for operating the brakes of horse-cars; and it consists in the novel arrangement of gearing to facilitate the winding and unwinding of the brake-chains; and in the construction and arrangement of a guard, to prevent passengers from leaning against the gearing; and of devices whereby the latter may be readily attached to, and detached from, the platform-rail of any horse-car of ordinary construction.

Referring to the accompanying drawing, A designates the fender or guard of a car-platform, to which is secured the rail B. B' represents the vertical shaft, through which is wound the brake-chain B², connected to the brake-lever in the ordinary manner. Upon the upper end of said shaft is fixed, in lieu of the brake-handle or crank, a pinion, b. C designates a large-sized spur-wheel, having its shaft-bearing in a block, D, and furnished with the crank E, as shown. The wheel C extends over the pinion b, and engages with an intermediate gear-wheel, E¹, which also engages with the pinion b, so that when the wheel C is turned motion will be conveyed to the brake-shaft B¹, and the latter quickly turned.

By this means the brakes may be operated with less trouble, and more rapidly than by the ordinary method.

The gearing might be arranged otherwise than as shown; but I adopt the arrangement illustrated, so as to allow the brakes to be

“put on” and “taken off” by turning the crank to the right and to the left, and thus occasion no mistake in persons unaccustomed to the use of the gearing.

Another object of this peculiar arrangement of gearing is to limit the space required upon the railing.

F designates a guard, consisting of a strip of sheet metal, or wood, if the latter be preferred, bent, as shown, and secured at its ends to the rail B. The object of this guard is to protect the driver or operator of the brake from the teeth of the wheels, and allow the latter to be turned without hindrance. The wheels E C are journaled to blocks D D', in order that they may be readily attached to, or detached from, the rail B, said blocks, for this purpose, being formed with recesses d, which receive said rail, as shown in Fig. 3. The blocks are secured in place by means of the bolts or screws d', inserted from the under sides thereof after the blocks have been fitted to the rail. The guard F may also be removable.

It will be observed that the gearing may be readily applied to any of the ordinary horse-cars, no drilling of the rail being required.

Having fully described my invention, what I claim as new, and desire to secure by Letters Patent, is—

1. The spur-wheel C, pinion b, and intermediate gear-wheel E¹, arranged as shown, in combination with the vertical shaft B¹ of a horse-car brake, as and for the purpose specified.

2. The fender F, attached to the rail of a car, substantially as and for the purpose specified.

3. The combination, with the gearing B C E, of the clamp D, consisting of the notched blocks d and bolts d', substantially as specified.

In testimony that I claim the foregoing I have hereunto set my hand this 17th day of November, 1873.

CHAS. HENRY HADLEY.
